UNITED STATES PATENT OFFICE.

GEORGE BRYANT, OF HIGHLAND PARK, ILLINOIS.

RAILWAY-CROSSING SIGNAL SYSTEM.

1,071,506.

Specification of Letters Patent.

Patented Aug. 26, 1913.

Application filed June 24, 1911. Serial No. 635,089.

To all whom it may concern:

Be it known that I, GEORGE BRYANT, a citizen of the United States, residing at Highland Park, in the county of Lake and 5 State of Illinois, have invented certain new and useful Improvements in Railway-Crossing Signal Systems, of which the following is a specification.

My invention relates to improvements in 10 railway crossing signal systems.

One of the objects of my invention is to provide a signal system whereby an alarm is sounded, at the road crossing of a railway, to warn drivers of teams, automobiles, or 15 other vehicles and other persons about to cross the track of the near approach of a car or train on said track.

Another, more specific, object of my invention is to provide, in a system of the 20 character described, means whereby trains approaching a crossing from either direction will automatically cause the energization of a signal instrumentality, such as a bell or the like, and cause the cessation of said signal at 25 or about the time when said train arrives at said crossing.

Other and further objects of my invention will become readily apparent to persons skilled in the art from a consideration of 30 the hereinafter contained description taken in conjunction with the drawings, wherein—

Figure 1 is a diagrammatic illustration of the electric circuits embodied in my alarm system; Fig. 2 shows a front elevation of an 35 instrument comprising two interlocking relays mounted for convenience on a single base of insulating material; Fig. 3 shows a side elevation of same; Fig. 4 is a broken-away portion of the relays showing the interlocking and circuit controlling mechanism; Fig. 5 is a similar view showing said parts in different positions of operation; Fig. 6 is a cross sectional view, taken on line 40 6—6 of Fig. 2; Fig. 7 is a section taken on line 7—7 of Fig. 2.

In all of the views, the same reference characters indicate similar parts.

I will first describe the mechanism of the various devices used in the system, so that 50 their operation will be understood, when they are referred to in the description of the system.

In my system, the operation of the alarm mechanism is initiated without the necessity for the moving train to directly operate or 55 move any mechanical switch closing or other

movable devices, and without interrupting or otherwise affecting the circuit communicating with the source of electric energy.

A pair of interlocking relays are preferably mounted upon a single base, 10, of insulating material, such as marble, slate, or the like.

The solenoid coil 11 is mounted in an iron frame 12, comprising brackets 13 and 14, 65 said brackets being joined by the flat iron plate 15, so as to almost complete the magnetic circuit. The responsive core 16 is adapted for sliding movement within the solenoid, and at its lower end is connected 70 to a switch-operating rod 17. The upper end of the core 16 is provided with a guiding pin 16^a. The lower end of the rod 17 is guided in a bracket 19, so that when the magnet is energized, the core 16 and rod 17 75 are raised vertically and returned by the effect of gravity. On the lower end of the rod 17 is adjustably secured a bracket 20. An insulated stem 21 is secured in an arm of bracket 20. One end thereof is bifurcated 80 as at 22, and between the prongs, thus provided, it carries a contact wheel 23, rotatably secured to the forked portion between the prongs thereof, and adapted freely to turn on the shaft 24. The opposite end of the 85 stem 21 is screw-threaded and carries two nuts 25 and 26 between which are fixed a spring brush or yielding electrical conductor 27 adapted to move freely over and make contact with the electrically conducting plate 28, in order to maintain the wheel 23 in electrical continuity with the circuit. The electrically conducting plate 28 is provided with a terminal 29 to which the circuit wires, in which the device is to be included, are connected. 95

The electric switch terminal coöperating with the wheel 23 consists of two arms 30—31 that converge laterally from a point near their ends toward each other to form a 100 fork, the two arms of which are so close together as to require a slight separation when the wheel 23 enters them. They are therefore yieldingly supported, as by plates 32 and 33, which are thin and of springy 105 material, such as phosphor bronze, so as to be easily moved when pressure is applied between the fork members. The plates 32 and 33 are riveted as at 34 to the arms 30 and 31 and to the plates of corresponding 110 thickness 35 and 36 respectively. Between the plates 35 and 36 is included a longer

plate 38 which extends to a point within the area partly surrounded by the members 30 and 31, constituting the fork. The plate 38 projects slightly beyond the point where 5 these members meet so as to afford an abutment or stop for the wheel 23, so that the wheel 23 will not separate the members 30 and 31 to such a degree as to open the circuits when it is forcibly inserted between 10 them.

A screw 39 passes loosely through the members 30, 31, and 38, and between one of the outer members and the end of the screw 39 is an open compression spring 40, held 15 by a nut 41 on the screw 39, so as to afford an elastic means for holding the members 30 and 31 in normal contact with the plate 38, and thereby to provide a yielding means to hold the elements 30 and 31 in contact 20 with the roller 23, whereby large areas of contact are provided and the surfaces maintained clean by the friction of the contacting parts. This electrical switch element is maintained on an insulating block 42, and 25 is provided with an electrical terminal post 43. The bracket 20 is provided with a laterally projecting arm or part 44, slotted, as at 45, and carrying a bearing pin 46. The rod 17 is provided with a spline 47 and a 30 feather 48 in the bearing 19 to prevent the rod from turning when it is moved vertically for the purpose of opening and closing the switch.

So far I have described one of the relays. 35 The other relay is a duplicate in every essential respect and I therefore indicate corresponding parts with the same reference characters with the addition of the exponent prime (').

40 A bearing bracket 49 is secured to the brackets 19—19' by screws 50—50'. To the bearing 49 is loosely secured a swinging latch member 51, pivoted as by a screw 52. Near the upper end of the latch member 45 51 is provided notch 53, providing upper and lower inclined shoulders 54 and 55 respectively, and near the midzone with a shoulder 56, the office of said shoulder being hereafter described.

50 For the purpose of conveniently distinguishing the relays, I will term one on the left the "west" relay and the one on the right the "east" relay. Fig. 4 shows that the west relay has been and is energized 55 and that the contact wheel 23' has been brought into conjunction with the fork switch element 30'—31' and has made electrical contact therewith, so as to complete the electric circuit through said contacts. 60 It will be noted that the latch member 51 has been tilted slightly toward the east relay by pin 46' of the west relay which comes into conjunction with the shoulder 54' of the latch, so that the shoulder 56 overlies 65 the pin 46 of the east relay, preventing the

lifting of the rod or stem 17 should the east relay now become energized, and therefore the east relay is locked against movement during the time when the west relay is so energized. It will be observed that the shoulder 54' is inclined or slanting, and that the pin 46' has not left the shoulder, in the position shown in Fig. 4. If, now, the east relay be energized before the west relay is deenergized, when the latter is deenergized, 70 the latch 51 will be thrown over to the position shown in Fig. 5, whereby the pin 46' has entered the slot 53' between the shoulders 54' and 55'. It is there held against further movement, in either direction, by 75 the contact of the pin 46' with the shoulder 56 of the energized, east relay. If, now, the circuits for both relays be opened, then the parts will fall by the effect of gravity to the positions shown in Fig. 2. In every 80 instance, it is the relay through which the current first flows that will operate the switch to throw in the auxiliary circuit, and if the other associate relay should be energized during the time that the first relay is 85 energized, or before the first relay has been deenergized, the second relay is locked against operative movement, even if it continues in energization after the deenergization of the relay first to operate and is thus 90 prevented from closing its subsidiary circuit, for a purpose to be hereinafter 95 described.

Now, referring to Fig. 1, in which my system is schematically shown, 105 is a trolley 100 wire, bridged between points 106 and 107 by a branch wire 105'. The points 106 and 107 are located at a distance remote from the road crossing at which it is desired to ring the alarm bell until the car has reached 105 the crossing. 108 is the highway crossing. From these points, respectively, sections 109 and 110 of the trolley wire are extended, to the road crossing, and are overlapped and secured in such way, at the road crossing, 110 that the trolley wheel will make contact with both of the sections for a short period of time, as shown at 111. The branches 109 and 110 are connected to the main trolley wire 105 through resistances R and R', which 115 shall be of such carrying capacity as to be able to carry the current necessary for supplying the cars between the points 106, 107, and 111 respectively. Around the resistances R and R', at each end, are connected 120 switch magnets 112 and 112', respectively. Between the points 106 and 113, is connected the coil for the switch magnet of the west relay, and between points 107 and 113' is connected the coil of the switching magnet 125 of the east relay. A responsive armature 114 is pivoted, as at 115, to a standard or support 116. It is normally held in raised position by spring 117 against the stop 118. Switch terminals 119 and 120 are adapted to 130

be closed by the armature 114, or any suitable switch lever operated thereby, as soon as the electromagnet 112 is energized. The circuit is adapted to be opened by the retraction of the armature 114 by the spring 117, when the said magnet is deenergized. A wire 121 is connected to the trolley 105 and to the switch terminal 119. A wire 122 connects switch terminal 120 to the contact 43 of the west relay. The contact 29 of the relay switches is common to both relays and is connected to the bell terminal 73 by a wire 123, the remaining terminal 74 having connection to the ground by wire 124 through a series of incandescent lamp resistances 125. In the present instance, the west relay coil 11' has one terminal connected to the contact 43. The east relay coil has one terminal connected to contact 43'. The remaining terminals of said coils are connected together as at 130 and this junction point is connected to the ground by wire 131 through a series of resistance lamps 132. If desirable, wire 131 could be connected to wire 124 and only a single series of resistance lamps 125 used. I have shown two series of lamps for sake of clearness of illustration.

The operation of the system is as follows: Assuming that the car is going east and has passed the point 113, which as a matter of fact, is substantially the point 106, then the current necessary for operating the car will pass through the resistance R over the branch 109, through the car motor to the ground, the branch 109 being separated between the points 106 and 113, but bridged between these points by resistance R. The coil 112 being parallel with the resistance R, sufficient current will pass through the coil to energize and attract its responsive armature 114 and close the circuit between the terminal 119 and 120. The circuit is thus closed between the trolley wire and the ground as follows: wire 121, 119 to 120 through switch lever 114, by wire 122 to point 43 of the west relay, thence through coil 11' to ground, over wire 131 and through lamps 132, thus energizing the west relay and causing it to raise its armature into position shown in Fig. 4, bringing switch members 23 and 30—31 into contact. It therefore closes the circuit through the bell 62, from point 43 to point 29, by wire 123, through the bell, and by wire 124, through lamps 125 to ground 126. In usual fashion, the bell short circuits its own magnet as the gong is struck causing the striker to drop back and break the short circuit and ready to strike another blow. By this means, a rapid succession of blows are imparted to the gong by the alarm bell, located at the highway crossing. The bell will continue to ring during the time the magnet 112

is energized or so long as the train or car 65 has electrical communication with branch 109 of the trolley wire 105. A train coming from the opposite direction cannot interfere with the operation of the bell. In order that the east bound car, in the present example, may not continue to cause the bell to ring after the car has passed the crossing, the east relay should be energized before the west relay is deenergized, and for this purpose, I provide, as a means, the closing of 70 the east circuit by lapping the branches 109 and 110 so that for a short period of time both relays are energized, then the west relay shall become deenergized.

In Fig. 4, both relays may be energized, 80 but the armature of the east relay is not operative being locked by the shoulder 44 of the latch 51, overlying pin 46. When the trolley wheel of the east bound car leaves the branch 109, current will no longer flow 85 over this branch, the circuit being now open at 111, the armature will be retracted by spring 117, and the circuit to the west relay will be opened. The armature of the west relay will now fall to the position shown 90 in Fig. 5, opening its own contact, but still holding the east relay locked and preventing the operation of the east circuit while the east bound car is between the crossing and the point 113'. When the car reaches this 95 point, both relays will be deenergized, and the relays will therefore have their parts returned to positions shown in Fig. 4, and current will no longer pass over the branches 109 or 110, nor over any of the signal 100 circuits.

When a car is going from east to west, it, in association with the apparatus, performs the same signaling function as clearly obvious from the foregoing illustration and 105 from the drawings.

While I have described a single embodiment of my invention it will be apparent that changes may be made in the details thereof without departure from the spirit of 110 the invention and within the scope of the appended claims.

What I claim is:

1. In a system of the character described, a trolley wire having sections insulated 115 from each other at a highway crossing, the trolley ends beyond said sections being electrically connected, connections between each section and the trolley including an electro-responsive device, a signal initiating circuit 120 controlled by each said electro-responsive device, signal-initiating means including an electro-responsive device in each said signal initiating circuit, means for mutual control between said signal-initiating means, and 125 signaling means controlled by said signal-initiating means.
2. In a system of the character described,

- a trolley wire having sections overlapping and insulated from each other at a highway crossing, the trolley ends beyond said sections being electrically connected, connections between each section and the trolley including an electro-responsive device, a signal initiating circuit controlled by each said electro-responsive device, signal-initiating means including an electro-responsive device in each said signal initiating circuit, means operable by simultaneous contact of a car-carried part with both sections, due to said overlap thereof, for mutual control between said signal-initiating means, and signaling means controlled by said signal-initiating means.
3. In a signal system, the combination with a trolley wire and a communicating car, of two trolley wire branches extending along the path of the trolley wire from given points toward an intermediate point, said branches normally disconnected from each other; a bridge wire spanning said branches and connecting said trolley wires beyond said branches, a signal producing means located at said intermediate point, signal initiating means connected between said trolley wire and said respective branches adapted and arranged to be energized when said car is in electrical communication with either of said branches, and means for disabling the operation of the signal producing means when the car is about to break contact with one branch and make contact with the other branch to prevent operation of the signal when the car is leaving said intermediate point.
4. In a signal system, the combination with a trolley wire and a communicating car, of two separated trolley wire branches connected to the trolley wire at remote points, and extending toward an intermediate point from opposite directions, a bridge wire spanning said branches to complete the uninterrupted continuity of said trolley wire, a signal producing means located at said intermediate point, signal initiating means connected between said trolley wire and said branches, respectively, adapted and arranged to be energized, respectively, when said car is in electrical connection with either of said branches, a relay for each initiating means, for closing the circuit of the signal producing means, and means operated by the relay first energized for op-

eratively disabling the other relay until the car leaves both said branches.

5. In a signal system, the combination with a trolley wire and a communicating car, of two separated trolley wire branches, each connected to the trolley wire at remote points and extending toward an intermediate point from opposite directions, means, at said intermediate point, for connecting said branches together by the operation of the trolley wheel, a bridge wire spanning said branches to complete the uninterrupted continuity of said trolley wire, a signal producing means located at said intermediate point, signal initiating means connected between said trolley wire and said branches, respectively, adapted and arranged to be energized when said car is in electrical communication with the appropriate branch, a relay for each initiating means, and a trolley wheel carried by the car, adapted and arranged to close the circuit through the idle relay before the opening of the circuit of the energized relay to lock and disable the operation of the second relay while the car is in communication with the second said branch, and while leaving said intermediate point.

6. In a system of the character described, a trolley wire having sections insulated from each other at a highway crossing, the trolley ends beyond said sections being electrically connected, connections between each section and the trolley wire including an electro-responsive device, a signal circuit and a signal-initiating circuit appurtenant to each said section, both controlled by the electro-responsive device for that section, the signal circuits appurtenant to both sections having a portion in common, signal-initiating means including an electro-responsive device in each said signal-initiating circuit each operable to control the appropriate signal circuit, signaling means including an electro-responsive device in said common portion of the signal circuits, and means for mutual control between electro-responsive devices of the signal-initiating means.

In testimony whereof I hereunto set my hand in the presence of two witnesses.

GEORGE BRYANT.

In the presence of—

MARY F. ALLEN,
W. LINN ALLEN.
